United States Patent Office.

J. T. GREENWOOD, OF BELOIT, WISCONSIN.

Letters Patent No. 94,954, dated September 21, 1869.

IMPROVEMENT IN WASHING-MACHINES.

The Schedule referred to in these Letters Patent and making part of the same.

To all whom it may concern:

Be it known that I, J. T. GREENWOOD, of Beloit, of Rock county, in the State of Wisconsin, have invented certain new and useful Improvements in Washing-Machines; and I do hereby declare the following description and accompanying drawings are sufficient to enable any person skilled in the art or science to which it most nearly appertains, to make and use my said invention or improvements, without further invention or experiment.

The nature of my invention and improvements consists in the construction and arrangement of the improved washing-machine hereinafter fully described, in which—

Figure 1, of the drawings, is a perspective view of the said improved machine complete, and

Figure 2 is a vertical side section of the same.

Similar letters of reference indicate corresponding parts.

Letter A represents the frame or box.

B, the adjustable larger roller, provided with the crank *b*, which roller is attached to the pivoted levers C C, by suitable boxes, in which it is rotated by the said crank *b*.

D D are smaller rollers, pivoted to and revolving upon the inner ends of the springs *d d*, provided for that purpose.

H H is a revolving apron, passing around the rollers D D and guard-rollers E E, the apron H H being

actuated and carried by the roller B, when in use, which, as well as the rollers D D, are covered with canvas, or other suitable material, rendering their surfaces partially elastic, and also supplying greater friction for carrying the clothes back and forward on the apron H, which is elongated by passing around the guard-rollers E E, and thereby forming a sort of platform for sustaining the clothes at each side of the rollers while being washed.

The springs *d d* impart a sort of semi-elastic action to the rollers D D, while being actuated by the roller B.

The operation of this machine is as follows:

Fill the box or tub with suds up to the rollers E E, or thereabouts; place the garments or other articles upon the apron H H; bring down the roller B upon them, by means of the cross-handle of the levers C C, and rotate the roller B, by the crank *b*, backward and forward, turning the wash from time to time, as may be required, till the work is complete.

What I claim as my improvement, is—

The arrangement of the levers C C, in combination with the covered rollers B and D D, guide-rollers E E, and springs *d d*, when constructed and connected as shown and described.

J. T. GREENWOOD.
